Patented Sept. 27, 1921.

UNITED STATES PATENT OFFICE.

JOSEPH A. FREUND, OF NEWTONVILLE, MASSACHUSETTS.

PROCESS OF MAKING WATCH-PLATES.

1,392,007.

Specification of Letters Patent. Patented Sept. 27, 1921.

Application filed August 8, 1918, Serial No. 248,821. Renewed January 13, 1921. Serial No. 437,127.

To all whom it may concern:

Be it known that I, JOSEPH A. FREUND, a citizen of the United States, and resident of Newtonville, county of Middlesex, State 5 of Massachusetts, have made a certain new and useful Invention Relating to Processes of Making Watch-Plates, of which the following is a specification, taken in connection with the accompanying drawing, which 10 forms part of the same.

This invention relates to processes of making, jewelng and assembling the supporting or frame members of time pieces, such as the plates of watch movements so 15 that the jewel or other bearings in the dial plate and the coöperating bridge members can be readily and accurately alined and uprighted. The dial plate which is preferably a number of times as thick as the bridges 20 may be formed with a series of steady pin and locating holes as by jig drilling the same therein and each of the bridges which are preferably formed of relatively thin 25 sheet metal stock of substantially uniform thickness may be formed with similarly located steady pin holes which, if desired, may be drilled in the bridges by using the same drill jig which was used for drilling the dial plate. It is sometimes possible to 30 secure still greater accuracy in these bearings by simultaneously drilling the corresponding locating and steady pin holes in the dial plate and one or more of the bridge members which for this purpose may be 35 simultaneously assembled in connection with a suitable drill jig plate for example. Each 40 of the bridge members may in such ways be formed with two or more locating steady pin holes in the same relative location as the corresponding holes in the dial plate so as to aline these members by the use of disengageable or other steady pins when the 45 watch movement is assembled. Preferably after the usual recessing operations the dial 50 plate and bridges may advantageously be jeweled on a set of jewelng quills, each of which may be formed with quill alining pins adapted to coöperate with the steady pin 55 holes in the dial plate and bridges, which thus act as locating holes to accurately 60 mount or locate the jewel and other bearings with reference to these steady pin holes. This 65 automatically locates the bearings in the same position in the dial plate and coöperating bridge so that when the movement 70 is assembled these parts are brought into 75 alignment by the pins in the locating steady pin holes so as to insure the accuracy and 80 uprighting of these bearings and greatly promote interchangeability in such high 85 grade watch movements.

In the accompanying drawing showing in a somewhat diagrammatic way methods of carrying out this process, Figure 1 is a sectional view through jig drilling devices 65 which may be used for drilling such locating steady pin or other holes in the dial plates, this view being taken substantially along the line A—A of Fig. 7.

Fig. 2 is a corresponding view of the drilling devices as they may be used for drilling the bridge members.

Fig. 3 is a corresponding view through jig drilling devices which may be used for simultaneously drilling the dial plate and 75 one or more bridge members therefor.

Fig. 4 is a partial sectional view taken along the same line showing the dial plate and the jewelng quill in connection therewith.

Fig. 5 is a similar view showing this quill 80 used for positioning the corresponding jewel in the bridge member.

Fig. 6 is a sectional view taken along the same line showing the plates assembled to 85 form the watch movement; and

Fig. 7 is a face view of these assembled parts.

It is advantageous to use the steady pin holes or devices which may be employed to 90 insure the alinement of the bridge members and dial plate of the watch movement to locate the jewel and other bearings in these watch plates during the manufacturing operations. For this purpose it is advanta- 95 geous to form a series of steady pin holes in the dial plate 1 of brass or other suitable material so located that two or more coöperate with each of the bridge members pref- 100 erably in amply separated position to insure the desired alinement of each bridge mem- 105 ber with the dial plate. The bridge mem- bers may, of course, be given any desired form and preferably extend substantially across the dial plate as indicated in the case of the barrel bridge 2 and train bridge 3 in Fig. 7. These may be provided with the steady pin holes 5, 6, 7 in the case of the barrel bridge 2, and 8, 9, 10 in the case of the train bridge, the dial plate 1 having cor- 110 respondingly located steady pins 32 which may advantageously be disengageable steady

pins securely held in the steady pin holes exactly corresponding to those in the bridge members. The third bridge member or balance cock 4 indicated may have the steady pin holes 11, 12, 13 at sufficient distances apart to properly align the balance cock and hold it in desired position, when securing means, such as the screw 14, is tightened. Similar screws, such as 15, 16, 17, may be used in the barrel bridge and screws 18, 19, 20 in the train bridge.

In this process the steady pin holes may be formed or drilled in the dial plate by the use of a drill jig plate, such as 57 indicated in Fig. 1, which may be firmly secured against the dial plate 1 as by the clamping flange 52 which may be formed on the drill support 53. This flange may have a series of securing slots 55 formed therein of bayonet slot form so that the securing pins 54 in the jig plate may be wedged around in these slots to securely clamp the parts together upon the dial plate. The drill support may, of course, extend sufficiently beneath the dial plate to amply support it during the drilling operation and this portion may be formed with holes, such as 56, corresponding to the guide holes, such as 58, in the jig plate above and having ample clearance so as not to interfere with the drilling operation. As indicated in Fig. 1, each of these steady pin holes may be accurately located and formed in the dial plate as by carefully drilling the same in connection with such a drill jig, the drill 66 being indicated as passing through and being guided by the hole 58 in the hardened drill jig plate so as to form the steady pin or locating hole 8' in the dial plate, the steady pin hole 9' being indicated as already formed in the dial plate in alignment with the guide hole 59 in the jig plate. In this way all of the locating or steady pin holes in the dial plate 1 may be formed in the dial plate in any desired positions, as indicated in Fig. 7, for instance, and it is desirable to have the drill jig engage the rear side of the dial plate with which the bridge members finally engage so that the steady pin holes are most accurately positioned on this side of the dial plate which is the base line or plane of the watch movement. The bridge members are preferably formed of sheet metal stock of any suitable composition which is preferably of uniform thickness, considerably thinner than the dial plate, and as indicated in Figs. 2 and 5 the train bridge 3 may have a thickness only a quarter or so of the thickness of the dial plate. The steady pin or locating holes may be formed in the bridge members in any desired way as by punching or drilling at any desired stage of the shaping or forming of the bridge members, and it is in some cases advantageous to form these steady pin holes in the bridge members by

drilling them in the same drill jig devices or by the use of the same drill jig plate used to drill the steady pin holes in the dial plate. Fig. 2 indicates the drilling of the steady pin holes in the train bridge 3 which may, if desired, be clamped against the jig plate 57 by any suitable clamping device holding the parts rigidly in desired position so that the drill 66 may be accurately guided by the hole 58 in the jig plate and thus form 75 the steady pin hole 8 in the desired part of the train bridge. The hole 9 in this bridge member is indicated as already having been formed in alignment with the hole 59 in the jig plate. These steady pin holes in the dial 80 plate and bridge members may be formed at any desired stage of the manufacturing process before jewelizing and when desired the steady pin holes may be formed in the dial plate after it has been recessed in any 85 desired machines in connection with the relatively large work holes, such as 47, 48, 49, which may be formed therein so as to properly locate the recesses, such as 25, 27, 50, for example. For some purposes, however, 90 it is desirable to have the recessing of the dial plate done after the steady pin or locating holes have been formed therein and these steady pin holes may be used to locate or align the dial plate in the machines in which 95 this recessing is performed which has the advantage of insuring the exact positioning of these recesses with reference to the jewel and other bearings and moving parts of the 100 watch.

In some cases it is more desirable to simultaneously drill the corresponding locating steady pin holes in the dial plate and one or more of the bridge members co-operating therewith. This may be done in 105 any suitable drilling devices in which the bearing supporting or frame members such as the dial plate and bridge members are maintained in the same relative position during the drilling as by clamping them 110 together, preferably in the same position in which they are finally assembled in the watch movement or other time piece. If desired, a jig drilling device may be used for this purpose of the character indicated in 115 Fig. 3. The dial plate 1 may be mounted in the drill support 73 and flange 72 and one or more of the bridge members, such as the train bridge 3 may be secured in position against the dial plate as by clamping the 120 same beneath the drill jig plate 77. As indicated this drill jig may have a depending positioning flange 75 in such position as to engage the edge of the bridge members which may be held in proper alignment 125 therewith in any desired way as by positioning pins or members extending through or around the bridge members such as the positioning pin 76, for instance. By turning or wedging the securing pins 54 around 130

in their bayonet slots 55 formed in the somewhat reduced securing flange 74 connected to the drill support, all of these members are tightly clamped together so that the dial plate and bridge members are securely held in contact throughout their base planes in the position in which they are finally assembled in the watch movement. The locating steady pin holes may then be simultaneously drilled in the one or more bridge members and dial plate as is indicated in the case of the hole 8' which is shown as being formed in the dial plate 1 by the drill 66 after the corresponding hole 8 has been drilled in the train bridge 3 in alinement with the guide hole 58 in the hardened drill jig plate 77. The coöperating steady pin holes 9, 9' are indicated as having been previously simultaneously drilled in alinement with the guide hole 59 in the jig plate. In this way if the dial plate and bridge members are securely clamped during the drilling operation there is no possibility that near the base plane of the watch the adjacent parts of the corresponding locating steady pin holes in the dial plate and bridge members will be out of alinement. This is because any slight angular deflection of the drill or its lateral movement in a guide hole of the jig plate correspondingly affects the location and direction of the steady pin holes thus simultaneously produced in the bridge member and in the dial plate beneath, so that by the use of suitable steady pins in these steady pin holes the watch plates may be accurately reassembled in this same position at any time. In this way a somewhat greater accuracy can be secured in drilling or forming these locating steady pin holes so that still greater accuracy is secured in locating and uprighting the bearings in the watch or other time piece, and it is of course understood that in order to secure these advantages it is desirable to correspondingly number or identify the simultaneously drilled dial plate and bridges therefor so that they will be assembled and used together.

It is advantageous to so form or locate the jewel or other bearings in the watch plates that the corresponding bearings are exactly located with reference to the steady pin holes controlling the assembly of the plates, and this may be conveniently effected by using a series of jewel quills having quill alining pins adapted to coöperate with the steady pin holes formed in the plates as above described. Fig. 4 indicates a jewel quill 60 formed with a series of projecting quill alining pins, such as 68, 69, adapted to coöperate with the dial plate locating steady pin holes 8', 9', etc., and which are in the same relative positions as the steady pin holes 8, 9 and 10, for instance, indicated in Fig. 7. These quill alining pins can thus positively aline the dial plate on the quill to which it may be held by any suitable retainers or holding dogs screwed or otherwise clamped to the quill. The quill alining pins are of course so located in the quill in which any particular jewel is set that this jewel is in the center of this jewel quill, and as indicated in Fig. 4 the dial plate is so alined or centered with respect to the jewel quill as to bring the center jewel or bearing into the axis of the quill. This allows the hole for this center jewel 21' to be opened out or counterbored in the usual way and the jewel inserted in the accurately counterbored portion of the hole and secured in position therein as by burnishing or spinning over the stock by a suitable tool such as 67, to form a retaining flange engaging the bevel of the jewel which is thus mounted in the dial side of this dial plate in proper relation to the rear side of the plate which forms the base plane of the watch movement and is forced closely against the accurate face of this jewel quill 60. The corresponding center jewel 21 may as indicated in Fig. 5 be set in the train bridge 3 on this same jewel quill 60, the alining pins 68, 69 fitting within the steady pin or locating holes 8, 9 in the train bridge and holding it in position in connection with any suitable retainers or holding dogs, so that the center jewel 21 is located exactly on the axis of this jewel quill. This jewel hole may then be opened up and counterbored in the same way and the jewel inserted and secured in position by a similar burnishing operation which insures the accurate location of these two center jewels in the dial plate and train bridge so that they necessarily come into exact alinement and uprighted position when the parts are assembled by bringing the steady pin holes into alinement as indicated in Fig. 6, for instance. As therein shown the steady pins 32 which may have the reduced ends 33 are forced tightly into each of the steady pin or locating holes in the dial plate 1 so that their cylindrical portions project somewhat beyond the base plane or rear face of the dial plate and engage the corresponding steady pin holes 8, 9 in the train bridge 3, for example, to accurately aline it and its jewel bearings with respect to the corresponding bearings in the dial plate.

By using relatively thin uniform thickness bridge members of this general character any bridge member, such as the train bridge 3, may be mounted on a jewel quill by clamping one face against the accurate supporting face of the quill and this necessarily brings the opposite face of the bridge member into position parallel to the quill face so that the axis of each jewel bearing is properly uprighted or located perpendicular to the face of the bridge member which en-

120
125
130

gages the dial plate. Of course each of the other jewels in the train bridge, such as the jewel 51, may be similarly located and mounted on another jewelizing quill which 5 has its alining pins so located as to bring this jewel into the quill axis, and the jewel or other bearings may be located or formed in the other bridge members and dial plate in similar ways. Instead of permanently 10 mounting the jewels directly in the watch plates they may of course be located therein by counterboring the bridge members or other plates so that they accommodate the removable or other settings of the bearing 15 jewels of any suitable character, such as the setting of the cap jewel or other bearing jewel 22 shown in Fig. 7 as secured to the plate by the securing screws indicated. Thus it is possible to drill and accurately 20 jewel the watch plates or locate the bearing jewels with respect thereto and at the same time insure the accuracy and uprightness of the jewel and other bearings therein by using as steady pin holes in assembling the 25 watch plates the locating holes by which the jewel or other bearings were formed or located, so that the interchangeability of the watch plates produced is greatly promoted in this high grade of movements while at 30 the same time their manufacture is correspondingly simplified.

This invention has been described in connection with a number of illustrative parts, forms, arrangements, proportions, materials, 35 machines, apparatus and orders of steps, to the details of which disclosure the invention is not of course to be limited, since what is claimed as new and what is desired to be secured by Letters Patent is set forth in the 40 appended claims.

1. The process of forming and jeweling watch plates which comprises forming a corresponding series of steady pin locating holes in the dial plate and in the thin substantially uniform thickness bridge members 45 by boring such steady pin holes through the same drill jig plate which is secured in alinement with the rear side of the dial plate against which the bridge members are secured in the watch movement, recessing the dial plate and bridge members and jeweling them on a series of jewelizing quills, each of which is formed with quill alining pins co-operating with the steady pin holes in one 50 of said bridge members to center with respect to said jewelizing quill one of the bearings in said bridge member and counterboring and setting the jewel in said bearing, and mounting the dial plate on said jewelizing quill and clamping the rear face of said dial plate against the face of said quill and inserting said quill alining pins in the corresponding steady pin holes in said dial plate to center with respect to said jewelizing 55 quill the corresponding bearing in said dial 60 plate and counterboring and setting the jewel in said bearing to insure the accuracy and uprightness of the bearings in the said watch plates when they are assembled and held in alinement by steady pins engaging the corresponding steady pin locating holes in said bridge members and dial 65 plate.

plate and counterboring and setting the jewel in said bearing to insure the accuracy and uprightness of the bearings in the said watch plates when they are assembled and held in alinement by steady pins engaging the corresponding steady pin locating holes in said bridge members and dial plate.

2. The process of forming and jeweling watch plates which comprises forming a corresponding series of steady pin locating holes in the dial plate and in the thin substantially uniform thickness bridge members, recessing the dial plate and bridge members and jeweling them on a series of jewelizing quills, each of which is formed with quill alining pins co-operating with the steady pin holes in one of said bridge members to center with respect to said jewelizing quill one of the bearings in said bridge member and counterboring and setting the jewel in said bearing, and mounting the dial plate on said jewelizing quill and inserting said quill alining pins in the corresponding steady pin holes in said dial plate to center with respect to said jewelizing quill the corresponding bearing in said dial plate and counterboring and setting the jewel in said bearing to insure the accuracy and uprightness of the bearings in the said watch plates when they are assembled and held in alinement by steady pins engaging the corresponding steady pin locating holes in said bridge members and dial plate.

3. The process of forming and jeweling watch plates which comprises forming a corresponding series of steady pin locating holes in the relatively thick dial plate and in the thin substantially uniform thickness bridge members by boring such steady pin holes in said dial plate from the rear side of the dial plate against which the bridge members are secured in the watch movement, and jeweling the dial plate and bridge members on a series of jewelizing quills, which comprise similarly located quill alining pins co-operating with the corresponding steady pin holes in one of said bridge members and in said dial plate to center the corresponding bearings thereof and counterboring and setting the jewels in said bearings to insure the accuracy and uprightness of the bearings in the said watch plates when they are assembled and held in alinement by steady pins engaging the corresponding steady pin locating holes in said bridge members and dial plate.

4. The process of forming and jeweling watch plates which comprises forming a corresponding series of steady pin locating holes in the relatively thick dial plate and in the thin substantially uniform thickness bridge members and jeweling the dial plate and bridge members on a series of jewelizing quills, which comprise similarly located quill alining pins co-operating with the corre-

- sponding steady pin holes in one of said bridge members and in said dial plate to center the corresponding bearings thereof and setting the jewels in said bearings to insure the accuracy and uprightness of the bearings in the said watch plates when they are assembled and held in alinement by the corresponding steady pin locating holes in said bridge members and dial plate.
- 10 5. The process of forming and jeweling watch plates which comprises forming a corresponding series of steady pin locating holes in the dial plate and in the bridge members and jeweling the dial plate and bridge members on a series of jeweling quills, which comprise similarly located quill alining pins coöperating with the corresponding steady pin holes in one of said bridge members and in said dial plate to center the corresponding bearings thereof and locating the jewels in said bearings to insure the accuracy and uprightness of the bearings in the said watch plates when they are assembled and held in alinement by the corresponding steady pin locating holes in said bridge members and dial plate.
- 15 6. The process of forming and jeweling watch plates which comprises forming a corresponding series of steady pin locating holes in the dial plate and in the bridge members and jeweling the dial plate and bridge members on a series of jeweling quills, each of which is formed with quill alining pins coöperating with the steady pin holes in one of said bridge members to center with respect to said jeweling quill one of the bearings in said bridge member and counterboring and setting the jewel in said bearing, and mounting the dial plate on said jewel quill and clamping the rear face of said dial plate against the face of said quill and inserting said quill alining pins in the corresponding steady pin holes in said dial plate to center with respect to said jewel quill the corresponding bearing in said dial plate and counterboring and setting jewel in said bearing to insure the accuracy and uprightness of the bearings in the said watch plates when they are assembled and held in alinement by the corresponding steady pin locating holes in said bridge members and dial plate.
- 20 7. The process of forming and jeweling watch plates which comprises forming a corresponding series of steady pin locating holes in the dial plate and in the bridge members and jeweling the dial plate and bridge members on a series of jeweling quills, each of which is formed with quill alining pins coöperating with the steady pin holes in one of said bridge members to center with respect to said jeweling quill one of the bearings in said bridge member and counterboring and setting the jewel in said bearing, and mounting the dial plate on said jewel quill and clamping the rear face of said dial plate against the face of said quill and inserting said quill alining pins in the corresponding steady pin holes in said dial plate to center with respect to said jewel quill the corresponding bearing in said dial plate and counterboring and setting jewel in said bearing to insure the accuracy and uprightness of the bearings in the said watch plates when they are assembled and held in alinement by the corresponding steady pin locating holes in said bridge members and dial plate.
- 25 8. The process of forming, jeweling and assembling watch plates which comprises forming a corresponding series of steady pin locating holes in the dial plate and in the coöperating bridge members, using said holes in each of said bridge members as locating holes to mount the same on jeweling quills to jewel said dial plate and assembling said watch plates and holding them in alinement by using said locating holes as steady pin holes to insure the accurate location and uprightness of the bearing jewels.
- 30 9. The process of forming, jeweling and assembling watch plates which comprises forming a corresponding series of locating holes in the dial plate and in the coöperating bridge members, using said holes in each of said bridge members as locating holes to mount the same on jeweling quills to jewel 100 said bridge member, using the corresponding holes in said dial plate as locating holes to mount said dial plate on each of the same jeweling quills to correspondingly jewel said dial plate and assembling said watch plates and holding them in alinement by using said locating holes as steady pin holes to insure the accurate location and uprightness of the bearing jewels.
- 35 10. The process of forming, jeweling and assembling watch plates which comprises forming a corresponding series of locating holes in the dial plate and in the coöperating bridge members, using said holes in each of said bridge members as locating holes to mount the same on jeweling quills, using the 105 corresponding holes in said dial plate as locating holes to mount said dial plate on each of the same jeweling quills and assembling said watch plates and holding them in alinement by using said locating holes to insure the accurate location and uprightness of the bearing jewels.
- 40 11. The process of forming, jeweling and assembling watch plates which comprises forming a corresponding series of steady pin locating holes in the dial plate and in the coöperating bridge members, using said holes in each of said bridge members as locating holes to mount the same on jeweling quills to locate the bearing jewels in said 120
- 45 12. The process of forming, jeweling and assembling watch plates which comprises forming a corresponding series of steady pin locating holes in the dial plate and in the coöperating bridge members, using said holes in each of said bridge members as locating holes to mount the same on jeweling quills to locate the bearing jewels in said 125
- 50 13. The process of forming, jeweling and assembling watch plates which comprises forming a corresponding series of steady pin locating holes in the dial plate and in the coöperating bridge members, using said holes in each of said bridge members as locating holes to mount the same on jeweling quills to locate the bearing jewels in said 130

- bridge member, using the corresponding holes in said dial plate as locating holes to mount said dial plate on the same jeweling quills to correspondingly locate the corresponding bearing jewels in said dial plate and assembling said watch plates and alining them by using said locating holes as steady pin holes to insure the accurate location and uprighting of the bearing jewels.
12. The process of forming and assembling watch plates which comprises forming a corresponding series of locating holes in the dial plate and in the coöperating bridge members, using said holes in each of said bridge members as locating holes to mount the same on supports to locate the bearings in said bridge member, using the corresponding holes in said dial plate as locating holes to mount said dial plate on the same supports to correspondingly locate the corresponding bearings in said dial plate and assembling said watch plates and alining them by using said locating holes to insure the accurate location and uprighting of the bearings.
13. The process of forming and jeweling watch plates which comprises forming a corresponding series of locating holes in the dial plate and in the coöperating bridge members, using said holes in each of said bridge members as locating holes to mount the same on jeweling quills to locate the bearing jewels in said bridge member and using the corresponding holes in said dial plate as locating holes to mount said dial plate on the same jeweling quills to correspondingly locate the corresponding bearing jewels in said dial plate to insure the accurate location and uprighting of the bearing jewels.
14. The process of forming, jeweling and assembling watch plates which comprises forming a corresponding series of steady pin locating holes in the dial plate and in a thin substantially uniform thickness coöperating bridge member, using said holes in said bridge member as locating holes to mount the same on jeweling quills to jewel said bridge member, using the corresponding holes in said dial plate as locating holes to mount said dial plate on jeweling quills, to correspondingly jewel said dial plate and assembling and alining said watch plates by using said locating holes as steady pin holes to insure the accurate location and uprighting of the bearing jewels.
15. The process of forming and locating the bearings in the bearing supporting members of watches and other time pieces which comprises simultaneously forming a series of corresponding locating holes in said members, locating the corresponding bearings in said members from said locating holes in said members to insure the accuracy and uprighting of the corresponding bearings in said members when they are assembled and held in alinement by the corresponding locating holes in said members.
16. The process of forming and jeweling the bearing supporting members of time pieces which comprises assembling said members in a jig drilling device and simultaneously drilling a series of corresponding steady pin locating holes in said members, jeweling said members on a series of jeweling quills formed with quill alining pins co-operating with the steady pin holes in said members to center with respect to said jeweling quill the bearings in the coöperating members to insure the accuracy and uprighting of the corresponding bearings in said members when they are assembled and held in alinement by steady pins engaging the corresponding steady pin holes in said members.
17. The process of forming, jeweling and assembling watch plates which comprises temporarily assembling said plates in a jig drilling device and simultaneously drilling a series of corresponding steady pin locating holes in said plates, using said holes as locating holes to mount said plates on each of the same jeweling quills and jeweling said plates thereon and assembling said watch plates and holding them in alinement by using said locating holes as steady pin holes to insure the accurate location and uprighting of the bearing jewels.
18. The process of forming, jeweling and assembling watch plates which comprises temporarily assembling said plates and simultaneously forming a series of corresponding steady pin locating holes in said plates, using said holes as locating holes to mount said plates on jeweling quills and jeweling said plates thereon and assembling said watch plates and holding them in alinement by using said locating holes as steady pin holes to insure the accurate location and uprighting of the bearing jewels.
19. The process of forming and assembling watch plates which comprises simultaneously forming a series of corresponding steady pin locating holes in said plates, using said holes as locating holes to mount said plates on quills and locating the jewel or other bearings in said plates, and assembling said watch plates and holding them in alinement by using said locating holes as steady pin holes to insure the accurate location and uprighting of the bearings.
20. The process of forming and assembling the bearing supporting plates of watches or other time pieces which comprises simultaneously forming a series of corresponding locating holes in said plates, using said holes as locating holes to locate the jewel or other bearings in said plates, and assembling said plates and holding them in alinement by using said locating holes to

insure the accurate location and uprighting of the bearings.

21. The process of forming, jeweling and assembling watch plates which comprises forming a corresponding series of locating holes in the dial plate and in a coöperating bridge member, using said holes in said bridge member as locating holes to mount the same on jeweling quills to locate the bearing jewels in said bridge member, using the corresponding holes in said dial plate as locating holes to mount said dial plate on jeweling quills to correspondingly locate the bearing jewels in said dial plate and assembling and alining said watch plates by using said locating holes to insure the accurate

location and uprighting of the bearing jewels.

22. The process of forming and jeweling watch plates which comprises forming a corresponding series of locating holes in the dial plate and a coöperating bridge member, using said holes in said bridge member as locating holes to mount the same on jeweling quills to jewel said bridge member and using the corresponding holes in said dial plate as locating holes to mount said dial plate on similar jeweling quills to correspondingly jewel said dial plate to promote the accurate location of the bearing jewels.

JOSEPH A. FREUND.
